DESIGN FOR A RUG.

40,912.

Specification for Design. Patented Sept. 20, 1910.

Application filed July 26, 1910. Serial No. 574,022. Term of patent 7 years.

To all whom it may concern:

Be it known that I, JOHN H. WITZEL, a citizen of the United States, residing at 793 East One Hundred and Seventy-sixth street, borough of Manhattan, city and State of New York, have invented a new, original, and ornamental Design for Rugs, of which the following is a specification, reference being had to the accompanying drawing, forming part thereof.

The figure is a plan view of one of the like quarters of a rug, showing my new design.

I claim:

The ornamental design for a rug, as shown.

JOHN H. WITZEL.
